UNITED STATES PATENT OFFICE.

ANDREW R. RIDDERSTROM, OF NAHANT, MASSACHUSETTS, ASSIGNOR TO BEACON FOLDING MACHINE COMPANY, OF LYNN, MASSACHUSETTS, A CORPORATION OF MASSACHUSETTS.

FOLDING METHOD AND ARTICLE PRODUCED THEREBY.

Original application filed June 24, 1921, Serial No. 480,177. Divided and this application filed December 7, 1922, Serial No. 605,374. Renewed March 24, 1926

The present invention relates to methods of folding the margins of flexible sheet material, like shoe uppers, and pressing the folds or the like so formed and to articles produced by such methods. The invention is illustrated and described herein in connection with the folding and pressing of a binding strip around the edge of a boot or shoe upper to which it is attached, as in a copending application, Serial No. 480,177, filed June 24, 1921, of which the present application is a division.

In the manufacture of boots, and shoes it has been common practice to finish the edge of a part of a shoe upper by securing to one face of the part, along an edge thereof, a strip of binding, then to coat the strip with a cement which is normally wet and sticky and then to fold the free portion of the strip progressively around the edge of the shoe part and press it down upon the margin of the other face of said part. Cement of the type referred to, owing to its liquid character, is liable to become smeared more or less upon the shoe part; and besides, remains sticky only for a limited interval during which, of course, the folding and pressing must take place.

According to a feature of the present invention a binding strip coated with a cement which is normally dry and non-sticky, but may be rendered sticky by the application to it of heat, is used; and heat is applied progressively to the strip to liquefy or render the cement sticky. This method is not only much cleaner than the old, wet-cement method, but is much more convenient in that the dry-cemented work may be allowed to stand for an indefinite interval before being operated upon.

In the machine, chosen for illustration, by the use of which a dry-cemented strip may be folded in accordance with the present invention, the strip is first acted upon by a wiper, after which it is tightly gripped and pulled tight between a feed point and a plow. It is then folded over upon the leather sheet to which it is attached, being finally pressed down by a fold presser, the last-named element being maintained at a temperature sufficient to render the dry cement sticky.

In the drawings, Fig. 1 is a view in elevation, partly in longitudinal section, and with parts omitted, of a machine by the use of which dry-cemented work may be folded;

Fig. 2 is a plan of the forward portion of the machine; Fig. 3 is a section of a shoe upper, showing an unfolded binding strip attached thereto; Fig. 4 is a section similar to Fig. 3, showing the binding strip in finally folded position upon the upper; Fig. 5 is an enlarged detail, plan view, showing the operation of folding a binding strip attached to a shoe upper, many parts being omitted for clearness; and Fig. 6 is a vertical section taken substantially upon the lines 6—6 of Fig. 5, looking in the direction of the arrows.

The invention is illustrated in the accompanying drawings in connection with the folding of a binding strip 2, of cloth, silk and the like, around the edge 4 of a sheet of leather or other material 6, such as a boot or shoe upper. An edge 8 of the binding strip is sewed at 12 to a face 10 of the shoe upper along the edge 4, so that the sheet and the strip extend at an angle to each other from the secured-together edges 4 and 8. It will be understood that the invention is equally applicable to other articles than that which is herein chosen for purposes of illustration, and the elements of the article need not necessarily be of the relative dimensions shown. It may be desirable, for example, to fold an element of relatively large dimension over the edge of an element of relatively small dimension. For definiteness, the element that is to be folded will hereinafter be referred to in the specification and the claims as the "strip" and the element about the edge of which the strip is to be folded will be hereinafter referred to as the "sheet", "stock", "upper", "work", etc., though the adopted terminology may not be strictly applicable to the specific article which may be under consideration.

The shoe upper is initially placed upon a platform or support 24, Figs. 2 and 5, with the face 10 of the upper in contact with the support. An end of the free or unsecured edge 26 of the strip 2 is initially moved across and around the secured-together edges 4 and 8, and into the space between an interior side face 28 of a preferably toothed feed point 30 and a plow 32 that stands up integrally from a plate 34. The machine being set into operation, successive portions of the unsecured edge or portion of the strip 2, near the stitches 12, are intermittently wiped tightly across the secured-together edges 4 and 8, or

away from the stitches, as shown more particularly at 36, Fig. 4, by the combined action of a wiper 38 and a retainer 153 that presses down heavily at this time upon the upper directly opposite to the point of action of the wiper. It is very important to the subsequent operation that the strip be wiped very tightly. The retainer-operating mechanism will not be described herein as it forms no essential part of the present invention. The retainer is provided with teeth 232, the more firmly to hold the stock. In order to enable the wiper 38 to operate, the strip 2 is progressively moved lightly or loosely by the operator's fingers from the position of Fig. 3 more or less into the plane of the shoe-upper sheet 6, as the shoe upper is fed forward through the machine. The successively wiped portions are initially intermittently folded around the secured-together edges 4 and 8 by the plow 32, during its backward movement with the feed elements, as described in Letters Patent No. 1,527,396, granted February 24, 1925. The plow-folded portions of the strip are gripped intermittently between the interior side face 28, Fig. 6, of the feed point and the plow 32, becoming thereby pulled tightly. The intermittent wiping, and folding and gripping operations are performed upon the successive portions of the strip alternately during successive pauses in the feed. The plow-folded portions are advanced by the feed point and a co-operating feed block 41, that is carried integrally with the plow 32 upon a plate 34, to a combined folder and fold presser 42. The fold presser 42 folds the plow-folded portions of the strip further and presses them down against the other face 16 of the sheet, as shown in Fig. 4. The preferred fold presser 42 is described in the said Letters Patent and in Letters Patent No. 1,527,395, also granted February 24, 1925. These operations are continued in timed relation to one another until the whole strip has become folded, as described more fully in the said Letters Patent No. 1,527,396. Reference is made to the said Letters Patent for a fuller description of so much of the machine as is not fully disclosed herein, because unnecessary to an understanding of the present invention.

The preferred wiper 38 is also fully described in the said Letters Patent No. 1,527,396, and need not, therefore, be further described here.

The strip is dry-cemented. With the adhesive in this dry-cemented condition, the strip 2 cannot adhere to the sheet 6. By heating the fold presser during the fold-pressing action, the dry cement will become liquefied, and the parts so caused to adhere together. An electrical heating unit 550 is shown mounted in position in an oil cup 552 of the fold-presser cylindrical bearing 158. This construction provides a very compact, heated

fold presser. A thermostat 554, Fig. 1, maintains the temperature of the fold presser within predetermined limits through causing the making and breaking of contact members 556. The thermostat, contact members and wiring connections are contained within a box 558 mounted upon a bracket 560 secured to the frame of the machine, as shown in Fig. 2.

Many parts of the illustrative machine have been very briefly described, or not described at all, because not essential to an understanding of the present invention, and because other such parts are well known in machines of the prior art. A fuller understanding of the illustrative parts may be had by referring to the above-mentioned application and Letters Patent, though many parts shown and described in the said application and Letters Patent are not illustrated or described herein because not forming any essential part of the present invention.

Although the invention has been described above in connection with a special machine disclosed in the above-identified Letters Patent No. 1,527,396 and with a particular kind of work, therefore, it will be understood that this is for illustrative purposes only, and that the invention is of broader scope, unlimited except in so far as limitations may be specifically imposed in the appended claims.

The machine which has been shown and described above is not herein claimed but forms the subject-matter of co-pending application Serial No. 740,735, filed September 30, 1924, which, like the present application, is a division of application Serial No. 480,177, filed June 24, 1921.

What is claimed is:

1. The method of folding a dry-cemented strip around the edge of a sheet of material to one face of which, along said edge, an edge of the strip is secured so that the sheet and the strip extend from the secured-together edges at an angle to each other, said method comprising moving the dry-cemented strip across and around said secured-together edges, pressing the strip into even contact with the other face of the sheet, and heating the strip while pressing it to liquefy the cement.

2. The method of folding a dry-cemented strip around the edge of a sheet of material to one face of which, along said edge, an edge of the strip is secured so that the sheet and the strip extend from the secured-together edges at an angle to each other, said method comprising intermittently moving successive portions of the unsecured edge of the dry-cemented strip across the secured-together edges, folding the successively moved portions around the secured-together edges alternately with the intermittent movement of the said successive portions, pressing the folded portions into even contact with the

other face of the sheet, and heating the folded portions while pressing them to liquefy the cement.

3. The method of folding a dry-cemented strip around the edge of a sheet of material to one face of which, along the said edge, an edge of the strip is secured so that the sheet and the strip extend from the secured-together edges at an angle to each other, the said 5 method comprising feeding the sheet and the strip step by step, moving portions of the unsecured edge of the strip across the secured-together edges during pauses in the feed, folding the moved portions around the secured-together edges during pauses in the feed subsequent to the pauses during which they were moved across the secured-together edges, pressing the folded portions into even contact with the other face of the sheet, and 15 heating the folded portions while pressing them to liquefy the cement.

4. The method of folding material that comprises progressively folding successive portions of the material with a cement interposed between the folded portions of the material, the cement being normally in such condition that it is ineffective to cause the folded portions of the material to adhere together, rendering the cement effective, and pressing 20 the folded portions of the material together.

5. The method of folding material that comprises feeding the material, folding at a predetermined position in the line of feed successive portions of the material with a cement interposed between the folded portions of the material, the cement being normally in such condition that it is ineffective to cause the folded portions of the material to adhere together, rendering the cement effective, and pressing 35 the folded portions of the material together.

6. The method of folding material a portion of which is provided with a cement in such condition that it is normally ineffective 45 to cause the folded portions of the material to adhere together, the said method comprising progressively folding successive portions of the material with the cement interposed between the folded portions of the material, rendering the cement effective, and pressing 50 the folded portions of the material together.

7. The method of folding material a margin of which is provided with a cement that is normally in such condition that it is ineffective 55 to cause the said margin to adhere to the body of the material, the said method comprising progressively folding successive portions of the said margin over upon the body of the material with the cement interposed between the said margin and the said body, rendering the cement effective, and pressing the folded marginal portions and the said body together.

8. The method of folding material a margin 60 of which is provided with a cement that

is normally in such condition that it is ineffective to cause the said margin to adhere to the body of the material, the said method comprising feeding the material, folding at a predetermined position in the line of feed successive portions of the said margin over upon the body of the material with the cement interposed between the said margin and the said body, rendering the cement effective, and pressing the folded marginal portions and the said body together.

9. The method of folding a strip around the edge of a sheet of material to one face of which, along the said edge, the strip is secured, the said method comprising progressively folding successive portions of the strip around the said edge with a cement interposed between the strip and the sheet, the cement being normally in such condition that it is ineffective to cause the strip to adhere to the sheet, rendering the cement effective and pressing the folded strip and the sheet together.

10. The method of folding material a portion of which is dry-cemented that comprises progressively folding successive portions of the material with the dry cement interposed between the folded portions of the material, liquefying the dry cement, and pressing the folded portions of the material together.

11. The method of folding sheet material a margin of which is dry-cemented that comprises progressively folding successive portions of the dry-cemented margin over upon a portion of the body of the material with the dry cement interposed between the said margin and the said body portion, applying heat to the said margin to liquefy the dry cement, and pressing the folded margin and the said body portion together.

12. The method of folding material a margin of which is dry-cemented that comprises feeding the material, folding at a predetermined position in the line of feed successive portions of the dry-cemented margin over upon the body portion of the material with the dry cement interposed between the said portions of the margin and the said body portion, liquefying the dry cement, and pressing the successively folded marginal portions and the said body portion together.

13. The method of operating upon a piece of work consisting of a piece of sheet material to one face of which along an edge thereof a dry-cemented binding strip is attached which comprises folding successive portions of the strip into position to be pressed against the other face of the material, pressing the folded portions successively against said other face and applying heat progressively to the strip to liquefy the cement.

14. The method of operating upon a piece of work consisting of a piece of sheet material to one face of which along an edge thereof a dry-cemented binding strip is attached

which comprises progressively bending successive portions of the strip, applying heat progressively to the successively bent portions and pressing them against the other face 8 of the sheet.

15. The method of finishing a shoe upper that comprises coating a margin of the upper with an adhesive that is normally in such condition that it is ineffective to cause the said 10 margin to adhere to the body of the upper, folding the said margin over upon the body of the upper with the adhesive interposed between the said margin and the said body, rendering the adhesive effective, and pressing 15 the folded margin and the said body portion together.

16. The method of making shoe uppers which comprises coating with adhesive material one side of a strip, sewing a margin of the 20 coated strip to one face of the marginal portion of the upper, the coating being condi-

tioned so as not to stick normally to surfaces with which it contacts, folding the strip over the edge of the upper, and causing the adhesive coated portion of the strip to adhere to the opposite face of the marginal portion of the upper.

17. As an article of manufacture, a sheet of material and a strip stitched together along juxtaposed edges, the strip being coated with an adhesive that is normally conditioned so as not to stick to surfaces with which it contacts, the strip being adapted to be folded over the edge of the sheet and pressed into contact with the sheet, and the adhesive being adapted to be rendered sticky to cause the folded and pressed strip to adhere to the sheet.

In testimony whereof, I have hereunto subscribed my name this 4th day of December, 1922.

ANDREW R. RIDDERSTROM.
